UNITED STATES PATENT OFFICE

PETER KELLER, OF GERA, GERMANY, ASSIGNOR TO THE FIRM M. RUDOLF JAHR, OF GERA, GERMANY, A JOINT STOCK COMPANY OF GERMANY

METHOD FOR CARBONIZING WOOLEN FABRICS

Application filed December 27, 1929, Serial No. 417,016, and in Germany December 29, 1928.

My invention relates to improvements in apparatus for carbonizing woolen fabrics. In carbonizing apparatus for woolen fabrics comprising several chambers the fabric is 5 first freed of the major part of the water, whereupon it is subjected to preliminary drying, and thereafter passed through drying chambers heated at increasing temperatures, until finally it is exposed in a carbonizing chamber to the highest temperature needed in the process. By means of one or more fans air is blown into the chamber of highest temperature, and the said air flows in opposition to the fabric successively through 10 the chambers of lower temperatures. In the chambers of higher temperature the air vaporizes the wool fat, and the said fat is precipitated within the chambers of lower temperature while conglomerating into drops 15 spoiling the fabric. Various efforts have been made to overcome this difficulty, and yet it is necessary to throw the carbonizing apparatus out of operation after a comparatively short time for thoroughly cleaning 20 the same.

In the known method the air is thus passed through the chambers in opposition to the fabric because it is desired to heat the last or carbonizing chamber by means of air 25 which is as dry as possible. As distinguished from the method now in use I pass the air through the apparatus in the same direction as the fabric, the said air being supplied to the apparatus at the side where the fabric is 30 passed into the same, and it is gradually heated by providing heating means at the intake side of the first chamber and between the successive chambers. If in one of the 35 chambers wool fat has been vaporized and taken up by the air, it can not be precipitated within the apparatus, and it escapes therefrom in the form of vapor. Thus the cause of the formation of fat drops spoiling 40 the fabric is obviated. Further, by thus conducting and heating the air heating apparatus of even size can be used in all the chambers. In this respect my improved apparatus is superior to the old apparatus in which 45 fresh air is directly taken into the chamber of highest temperature, and in which there-

fore a very large radiator is needed for heating the air from normal to carbonizing temperature, while the following heating requires radiators of comparatively small size. To provide radiators of different size is 55 objectionable because the resistance opposed thereby to the flow of the air varies.

In my improved apparatus the air is first moderately heated, and thereafter the temperature is successively raised, until it is 60 brought to the high temperature necessary for carbonizing. In all the chambers radiators of even size may be used, which offer the same resistance to the flow of the air. The consumption of heat is comparatively 65 low. Thus fewer radiators of different type and size are needed, and as a matter of fact the carbonizing apparatus of different sizes can be constructed so that radiators of a few 70 different sizes or even a radiator of one size is needed.

For the purpose of explaining the invention an example embodying the same has been shown in the accompanying drawings in which the same reference characters have 75 been used in all the views to indicate corresponding parts. In said drawings,

Fig. 1 is a sectional elevation of the apparatus, and

Fig. 2 is a sectional elevation taken on the 80 line 2-2 of Fig. 1.

In the figures the path of the air has been marked by heavy lines.

In the construction shown in the figures the apparatus comprises a chamber I for preliminarily heating the fabrics, three drying chambers II, III and IV in which the temperature of the air is successively raised, and a carbonizing chamber V. 85

The said chambers of the apparatus are 90 provided by vertical partitions r^1 , r^2 , r^3 and r^4 extending from the top of the apparatus downwardly to points away from the bottom thereof. In addition near the left wall of each chamber partitions w^1 , w^2 , w^3 , w^4 and 95 w^5 are provided by means of which trunks k^1 , k^2 , k^3 , k^4 and k^5 are formed at the left side of each chamber, and the said partitions w^1 to w^5 are curved to the right at their top ends. The partition w^1 extends downwardly 100

to a point slightly below the intake a , and the partitions w^2 to w^5 extend downwardly to points spaced from the bottom of the apparatus thus providing passages for the transmission of air from one chamber to the next one.

Within the trunks k^1 to k^5 radiators h^1 , h^2 , h^3 , h^4 and h^5 are provided, and all the said radiators have the same size and the same 10 heating capacity.

Adjacent chambers are connected with each other by suction boxes s^1 , s^2 , s^3 and s^4 and each suction box s^1 , s^2 , s^3 and s^4 is connected by a suction passage q with the median part of one chamber and through a passage a^1 , a^2 , a^3 and a^4 with the succeeding chamber II, III, IV and V, and more particularly with the heating trunk k^2 , k^3 , k^4 and k^5 thereof. Each suction box s^1 , s^2 , s^3 and s^4 is 15 provided with a rotary valve or gate b^1 , b^2 , b^3 and b^4 for admitting a limited supply of fresh air to the air circulated through the apparatus. At the delivery side of each box a fan or blower v^1 , v^2 , v^3 and v^4 is provided by 20 means of which the air is drawn from one chamber and blown into the heating trunk k^2 , k^3 , k^4 and k^5 of the next chamber. In addition a suction box s and a fan v^5 are provided in connection with the chamber V for 25 drawing the air therefrom and delivering the same through a pipe z to the outer air.

The fabric x is taken into the apparatus and into the chamber I from the left side thereof, and it leaves the apparatus through 30 an outlet made at the bottom of the right wall of the carbonizing chamber V. The manner of passing the fabric through the apparatus is known in the art and I deem it not necessary to describe the same in detail.

40 The air is taken into the apparatus from the left side thereof at a , and it is immediately heated at comparatively low temperature by means of the radiator h^1 provided near the intake of the apparatus. The air is circulated 45 through the apparatus by means of the said fans v^1 to v^5 , and in the example shown in the figures one fan is provided between successive chambers.

50 The air flowing upwardly through the trunks k^1 to k^5 is distributed over the whole area of the chambers I to V and it flows downwardly within the said chambers to the intake pipes q of the suction boxes s^1 to s^5 . Thus the air circulates through the whole chamber, 55 and before flowing from one chamber into the next one it is heated by the radiator h^1 , h^2 , h^3 , h^4 and h^5 to higher temperature. Thus the temperature of the air is increased as the fabric moves through the apparatus.

60 As has been stated above all the radiators h^1 to h^5 have the same size, they require the same room, and therefore the resistance opposed to the movement of the air is alike. There is no possibility of 65 vaporized wool fat being precipitated, be-

cause the temperature of the air is not reduced while flowing through the apparatus, and on the contrary it is continuously increased. The wool fat is precipitated after the air has left the apparatus.

70

The drawings show the path of the air in heavy lines. Successive chambers are connected with each other at their bottoms, and therefore each suction box takes some air from the following chamber, as is indicated by the dotted lines y^2 to y^5 . The air which has thus been taken in by the fans is circulated through the chamber, and it does not get into the portion of the previous chamber through which the fabric is passed, but is directly blown upwardly through the heating trunk of the following chamber for being delivered into the same after being heated. Preferably the fans and suction boxes are located outside each chamber where ready access can be had thereto.

I claim:

1. The method of carbonizing fabrics which comprises passing the fabric to be carbonized through a series of separate zones in succession, passing heated air through said zones in like succession, and supplying sufficient additional heat to the air passing through said zones to prevent decrease in the temperature thereof.

2. The method of carbonizing fabrics which comprises passing the fabric to be carbonized through a series of separate zones in succession, passing heated air through said zones in like succession, and supplying sufficient additional heat to the air passing through said zones to effect progressive increase in the temperature thereof.

In testimony whereof I hereunto affix my signature.

PETER KELLER.
